SAFETY ATTACHMENT FOR HAND-FED MACHINES

Benjamin Wachs, Brooklyn, N. Y.

Application December 16, 1941, Serial No. 423,133

6 Claims.

(Cl. 74—615)

This invention relates to safety attachments for hand fed machines such as pressing, punching and stamping machines, either of the foot or power actuated type and the invention is more definitely directed to an improved safety device which functions to prevent injury to the operator feeding the stock to the machine by automatically pushing, sweeping or otherwise displacing the hand from a position between the movable and fixed elements of the machine as the former approaches the latter.

In machines of this character injuries frequently result from failure of the operator to withdraw his hand after the stock has been fed to the machine and before the movable tool closely approaches the fixed tool. The present invention, therefore, aims to provide as an attachment for such machines, an improved safety device including a swingably mounted hand engaging and displacing member which moves between the fixed and movable elements of the machine as the latter approaches the former so as to insure the displacement of the operator's hand and this without in any way interfering with the operator's vision or detracting from his effectiveness in feeding the stock to or removing the same from the machine.

The invention is further directed to a safety attachment of the indicated character which is readily adjustable to adapt the same for use with various types of tools fitted into and employed in connection with the fixed and movable elements of the machine.

The invention further comprehends a safety device of the character set forth which is comparatively simple in its construction and mode of operation and which is applicable to any of the usual machines of the type specified without requiring material alterations thereto or involving undue expense in attaching the same.

With the above enumerated and other objects in view, the invention is set forth in greater detail in the following specification and illustrated in the accompanying drawing in which:

Fig. 1 is a perspective view of a pressing machine equipped with a safety attachment constructed in accordance with the invention and illustrating the guard member in a retracted out-of-the-way position with the tools in separated relation.

Fig. 2 is a fragmentary side view thereof with the parts shown in the position illustrated in Fig. 1 of the drawing.

Fig. 3 is a similar view illustrating the guard

member moved to active position and with the movable tool engaging the fixed tool.

Fig. 4 is an enlarged fragmentary sectional view taken approximately on the line 4—4 of Fig. 3.

Fig. 5 is a fragmentary detail perspective view illustrating a modified form of the invention.

Referring to the drawing by characters of reference A designates generally a machine for pressing, punching, stamping or other equivalent purposes which includes a base B upon which is mounted and secured a fixed tool holder C supporting a fixed tool D. The machine is further provided with a superposed head E which has guidedly mounted therein for vertical movement a reciprocating tool holder F provided at its lower end with a chuck G in which a movable tool H is mounted so that upon each operation of the machine the movable tool H is advanced towards and away from the fixed tool D. The stock to be operated upon by the tool D and H is fed by hand to the machine and if the operator fails to withdraw his hand after the stock is fed and before the movable tool engages the fixed tool, injury may result.

The present invention comprehends a safety device as an attachment for this type of machine which device consists of a guard member J and which, as illustrated in the present embodiment, is in the form of a ball including upright parallel side arms 10 and 11 connected at the lower end by a bight portion 12. The upper portions of the side arms respectively extend through longitudinally spaced openings 13 formed in a rock shaft 14 which is journaled for rotatory movement in bearing members 15 secured to transversely spaced portions of the stationary head of the machine. The side arms are secured to the rock shaft 14 by lock screws 16 which are engaged in threaded openings 17 extending inwardly from the opposite ends of the rock shaft. This associates the guard member J with the rock shaft in such a manner as to permit of adjustment thereof with reference to the rock shaft to dispose the connecting bight portion 12 at various heights coinciding with the particular location of the fixed and movable tools B and H.

In order to provide means for swinging the guard member in opposite directions in a path intersecting the path of movement of the movable tool H, a coiled contractile spring 20 is anchored at one end as at 21 to a stationary part of the machine and the opposite terminal 22 engages the side arm 10, while an actuating member 23 carried by a reciprocating tool holder

F is provided with laterally projecting trunnions 24 respectively engaging the side arms 10 and 11. The spring 20 functions to normally retract the guard member J rearwardly to an out-of-the-way position when the movable tool holder F and tool H are raised and the tools are separated from each other.

The trunnions 24 engaging the side arms 10 and 11 of the guard member J effect forward swinging of said guard member between and forwardly beyond the edges H and D as the movable tool advances towards and engages with the fixed tool D. It thus follows that if the hand of the operator is located between the tools as the movable tool approaches the fixed tool, either the connecting bight portion 12 or arms 10 and 11 of the guard member J will engage with and push or displace the operator's hand when so located from between the edges to avoid possibility of injury. As the movable tool is retracted or ascends, the trunnions 24 of the actuating member 23 will permit the spring 20 to swing the guard member J rearwardly to retract the same to its rearwardly disposed out-of-the-way position.

From the foregoing it will thus be seen that the safety attachment consists of the actuator member 23 which is secured in any desired manner, such as by screws or bolts 25, to the reciprocatory tool holder F, the securing of bearing members 15 to the head E of the machine and the anchorage as at 21 to the rear terminal of the spring 20. When applied to the machine, the safety device functions to positively insure displacement of the operator's hand if located between the fixed and movable tools as they approach each other so as to prevent injury by failure of the operator to remove his hands in time.

In the modified form of the invention illustrated in Fig. 5 of the drawing, the spring is eliminated and in place of the trunnions 24, eye members 24A respectively surround the side arms 10 and 11 and are carried by and protrude laterally from the actuator member 23 and function upon downward movement of the movable tool to swing the guard member forwardly and upon upward movement to swing the guard member rearwardly. In all other respects, this form of the invention functions in a similar manner to that described for the previous form of the invention.

What is claimed is:

1. In a hand fed machine of the type in which a pair of tools are mounted for relative movement towards and away from each other, a safety device for protecting the hands of the operator feeding the stock between the tools including a guard member actuated by the machine in timed relation with the relative movement of the tools and mounted on a stationary part of the machine for swinging movement of said guard member from an inactive out-of-the-way position at one side of the path of relative movement of the tools between said tools as they approach each other and beyond said path to the opposite side thereof so as to engage with and displace the operator's hand located between the tools.

2. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and

mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools.

3. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools.

4. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

5. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

6. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

7. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

8. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

9. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

10. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

11. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

12. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

13. In a hand fed machine of the type which embodies a fixed tool and a tool movable towards and away from the fixed tool, a safety device for protecting the hands of the operator feeding the stock between the tools including a guard member actuated by the machine in timed relation with the movement of the movable tool and mounted on a stationary part of the machine for swinging movement of the guard member from an inactive out-of-the-way position at one side of the path of movement of the movable tool between said tools as the movable tool approaches the fixed tool and beyond the path of movement of the movable tool to the opposite side thereof so as to engage with and displace the operator's hand located between the tools, the actuation of said guard member effecting retractive movement thereof between the same to the out-of-the-way position as the movable tool is retracted from the fixed tool.

6. In a machine of the hand fed type which embodies a base supporting a fixed tool and a head having a reciprocating tool holder supporting a tool movable towards the fixed tool, a safety attachment for said machine for protecting the hands of an operator feeding stock to the machine including a U-shaped guard bail having upright side arms and a bight connecting the lower ends thereof, bearing means secured to the machine head, a rock shaft mounted in said bearing means having openings adjacent the opposite ends thereof through which the side arms of the guard bail extend, set screws carried by the rock shaft engaging said side arms to adjustably se-

5 cure the guard bail to the rock shaft and for mounting the guard bail for swinging movement to and from an inactive out-of-the-way position at one side of the path of movement of the movable tool between said tools and beyond the same at the opposite side thereof, means for normally retracting the guard bail to its inactive position and means secured to the reciprocating tool holder and engaging the side arms of the guard bail for swinging the same to engage with and displace the hand of an operator located between the tools as the movable tool approaches the fixed tool.

10 BENJAMIN WACHS.
